Inventor:
Esek Bussey.

United States Patent Office.

ESEK BUSSEY, OF TROY, NEW YORK.

Letters Patent No. 77,581, dated May 5, 1868.

IMPROVEMENT IN OVENS.

The Schedule referred to in these Letters Patent and making part of the same.

TO ALL WHOM IT MAY CONCERN:

Be it known that I, ESEK BUSSEY, of Troy, in the county of Rensselaer, and State of New York, have invented certain new and useful Improvements in Stove-Ovens; and I do hereby declare that the following is a full and exact description of the same, reference being had to the accompanying drawings, and to the letters of reference marked thereon, making a part of this specification, in which—

Figure 1 is a perspective view of said improvement in stoves.

Figure 2 is a separate perspective view of the portable oven thereof.

Figure 3 is a vertical sectional view of fig. 1, and

Figure 4 is a vertical transverse sectional view of aforesaid portable oven.

The same letters of reference indicate like parts in each of the said figures.

My said invention relates to drum or supplemental ovens, and the manner of construction, arrangement, and attachment of the same to stoves; and its nature consists in hinging or pivoting within said ovens a division or rack-plate, in such a manner that, when the whole unobstructed oven-capacity or space is required for use, the said plate may then be conveniently turned or folded close to the oven-side, substantially as hereinafter fully described, instead of being withdrawn entirely therefrom, as heretofore made necessary, in order to use the whole capacity of the oven.

The said invention also consists in the peculiarity of construction of the back part or end of said oven, and in the arrangement of the same in direct combination with the exterior wall or shell of heating-stoves, in manner substantially as hereinafter fully described and shown.

To enable others skilled in the art to make and use my said invention and improvements, I now proceed to fully describe the same.

In the annexed drawings, fig. 1 represents a heating-stove, of the usual known construction, and as having combined therewith an oven, C D.

This oven is constructed with flues, E E, surrounding it, which, when said oven is arranged in position for use with said stove, connects with its exit-flues, in manner as shown in figs. 1 and 3 of aforesaid drawings. Arranged within said oven, and hinged or pivoted to turn on journals *a a* therein, is a division-plate or rack, K, which is operated by a handle, M, formed at the end of one of said journals, which projects through the oven-side, and, when turned down for use, said rack-plate rests its front part on and is supported by the lugs *b b* affixed to the oven-sides in horizontal lines with the journals *a a*, so that the said plate is evenly supported by its said journals and lugs in a horizontal position for use, as shown in fig. 3, and when not used, it is then turned up or folded back, so as to leave the whole oven-space unobstructed, in manner as shown in fig. 2, and so obviating all necessity for removing said plate from the oven. This oven is supplementary or additional to heating-stoves, to thereby make such stoves more useful and convenient than heretofore.

Within the aforesaid oven there is also arranged or hinged, to turn upward and downward therein on journals or pivots *c c*, a boiler-hole cover, H, in manner as shown in figs. 2 and 3, for the purposes of covering a boiler-hole, H', therein. One of the said journals projects through the side of the oven, to thereby form a handle, N, by which to conveniently operate said cover, which, when the said boiler-hole is used to place vessels therein for heating water or for other purposes, is then turned up against the back part or side of the oven, so as to be no obstruction to the use of said boiler-hole, and thus avoiding a necessity of removing said covering-plate entirely from the oven, as heretofore, when using said boiler-hole.

The back part or end of the aforesaid oven D is made open, to thereby permit an increased and direct radiation of heat from the stove exterior wall or shell into said oven-space, when the oven is arranged in direct combination with said wall, P, in manner as seen in figs. 1 and 3; and arranged at the back part or open end of said oven there is a series or set of deflection-plates or slats, L L, placed horizontally across said open end, and inclined downward and inward to said oven-space, at an angle such that the rays of heat radiated from the stove-

shell or wall are deflected downward and into the lower parts of said oven, to thereby promote a circulation of heat therein sufficiently to equalize and maintain an even degree of heat throughout the said oven.

The said inclined series of plates or slats serves also as a direct guard to shield articles placed in the back parts of the oven from a too strong or burning heat.

This aforesaid oven, as thus constructed substantially, is arranged in position for use with heating-stoves, by placing its said back, end, or side in direct contact with the exterior wall or shell P of the stove, and connecting the oven-surrounding flues E E with the exit-flue of the stove, in manner substantially as shown in figs. 1 and 3, so that, while continued in such arrangement, the said oven-flue forms a part of the exit-flue of said stove, and when the further use of the said oven is not desired with the stove, it is then easily removed therefrom, and its place, as part of said exit-flue, is then filled by a suitable section of flue-pipe, the stove itself remaining unaltered.

What I claim as my invention, and desire to secure by Letters Patent, is—

1. In combination with an oven attached to stoves, I claim hinging or pivoting therein a division or rack-plate, K, so that it may, when not used, be folded therein close to the oven-side, in manner substantially as and for the purpose set forth.
2. In combination with a stove, I claim a drum-oven, having a slotted or open back or side, and arranged or placed directly beside and against the exterior wall or shell of the combustion or fire-chamber of said stove, in manner substantially as and for the purpose herein set forth.
3. In combination with a drum-oven, having an open back or side, and placed against the shell or plate of a stove, I claim the employment therein of a series of slats or plates L L, arranged in manner substantially as and for the purposes herein described.

ESEK BUSSEY.
